UNITED STATES PATENT OFFICE.

WILLIAM B. CHAPMAN, OF NEW YORK, N. Y., ASSIGNOR TO THE CHAPMAN ENGINEERING COMPANY, OF MOUNT VERNON, OHIO, A CORPORATION OF OHIO.

ASH-EJECTING APPARATUS FOR GAS PRODUCERS.

Application filed July 28, 1921. Serial No. 488,188.

To all whom it may concern:

Be it known that I, WILLIAM B. CHAPMAN, a citizen of the United States, residing at New York, in the county of New York and State of New York, have invented a certain new and useful Ash-Ejecting Apparatus for Gas Producers, of which the following is a specification.

One object of the invention is to convey 10 the ash mechanically from underneath the fuel bed of a gas producer to the space exterior to the side walls thereof in such manner that the ash will be automatically and uniformly removed at a rate commensurate 15 with its production, without the necessity of manual operation.

In this preferred form the invention is so constructed that the above results may be obtained independent of any motion of 20 heavy parts of the gas producer, and thus the side walls of the producer may be stationary and only such parts rotated as are provided directly to act upon the ash. In this way the initial cost of the apparatus is 25 much decreased, as well as the cost of maintenance and operation, since the expense is avoided of mounting the heavy parts of the producer for rotation, and providing additional power to drive them.

Another object of the invention is to effect 30 the removal of the ash from the space exterior to the bottom of the side walls of the producer, preferably after the ash has been pushed into this region by means as 35 above described, in order that the operations of removing the ash from underneath the fire bed of a stationary gas producer and from the space adjacent the bottom of the side walls thereof, may be conjointly performed.

Another object is to provide for the stirring 45 or agitation of the bed of ash within the producer, to break up any clinkers or the like, and produce uniform conditions within the producer so that the air blast will pass up through the ash substantially uniformly throughout the area of the producer, and thus promote uniform combustion therein.

Further objects and advantages of the invention will be in part obvious and in part specifically pointed out in the description hereinafter contained, which, taken in con-

junction with the accompanying drawings, discloses a preferred embodiment of the invention; such embodiment, however, is to be considered merely as illustrative of its principle. In the drawings:

Fig. 1 is a vertical central section of the lower portion of a gas producer having stationary side walls, and equipped with an ash-ejecting apparatus made in accordance with the invention.

Fig. 2 is a plan view of such ash-ejecting apparatus, shown detached.

Fig. 3 is a side view of the same.

The invention is disclosed in connection with a gas producer having side walls 1 mounted upon a base 2, through which an air and steam supply conduit 3 will ordinarily lead to a tuyère hood 4 disposed centrally within the side walls 1. In the operation of the producer the portion of the fuel bed above the level indicated approximately by line 5 (Fig. 1) will not have been completely burned, while the region within side walls 1 and beneath the line 5 will ordinarily be filled with ash which has descended from the zone of combustion after being burned as completely as possible.

The ash pit 6 of the producer in the present instance is provided by shaping the base or foundation 2 with a top wall 7 which underlies the side walls 1 and extends exterior thereto, to an annular wall 8 of the base 2, thus providing a trough-shaped portion 9 in the ash pit exterior to the side walls 1, and from which the ash produced within such side walls may be withdrawn. Ordinarily the ash pit will be utilized to afford a water seal for the interior of the producer, the side walls 1 in the present construction being provided with an annular, downwardly-extending lip 10 (Fig. 1) which projects into the ash pit 6, the approximate water levels within and without the side walls 1 being indicated by lines 11 and 12 (Fig. 1) respectively.

In accordance with the present invention the ash is moved outwardly from within the confines of the producer side walls 1 to the trough-shaped portion 9 of the ash pit which lies exterior thereto, in such manner that the heavy parts of the producer may remain stationary, and only such parts being moved as contribute directly to the removal

of the ash. In the form of the invention illustrated, an ash-ejecting beam 13 is mounted to work under the side walls of the producer, and is out-stroking in its action; thus, as the beam 13 revolves relative to the ash carried within the side walls 1, the ash on the forward side of the beam is forced outwardly under the lip 10 of the side walls into the trough-shaped portion 9 of the ash pit.

In order to avoid the necessity of movement of the heavy parts of the producer, the side walls 1 are supported in fixed position, as by means of pedestals 14 (Fig. 1) 15 extending from the foundation 2, and the ash-ejecting beam 13 is rotated at the speed necessary to remove the ash from underneath the side walls at the desired rate. In the present construction, movement is imparted to the ash-ejecting beam 13 through a gear ring 15 substantially concentric with side walls 1 and rotatably mounted adjacent the lower portion of such walls, as by means of suitable rollers 16 supporting the ring, 25 and further rollers 17, guiding its circular movements. A pinion 18 meshes with the gear ring 15, suitable means (not shown) being provided whereby the speed of rotation of the ring may be adjusted to remove 30 the ash at a rate conformable to the rate of gasification within the producer.

Thus, due to the fact that neither the side walls 1 nor the foundation 2 of the producer need be moved to assist in the removal of the ash, the expense is avoided of providing and maintaining special constructions to permit these parts to rotate, and the removal of the ash is effected by movement of the beam 13 and gear ring 15, 40 which are comparatively light in weight, of low initial cost, and which may be repaired or replaced with much less trouble and expense.

I prefer to dispose the ash-ejecting beam 13 substantially diametrically of the side walls 1, its opposite ends being bent upwardly and joined respectively to the adjacent portions of gear ring 15, and its central portion being provided with a hub 19 which loosely encloses the neck of the tuyère hood 4. Thus the beam 13 is normally supported entirely by ring 15, and runs clear of the neck of the tuyère hood as well as from the ash pit and side walls of 50 the producer; but if the beam 13 should be abnormally displaced laterally the neck of the tuyère hood may act as a stop to maintain it in position, and if the beam should tend to rise out of position the lip 10 will 55 act as a stop to prevent this movement, as well as the flanges on the neck of the tuyère hood (as shown in Fig. 1) which are disposed above and below, and slightly spaced from the hub 19. As shown in Fig. 2, the 60 outer ends 20 of the beam 13 may be curved 65

to increase its out-stroking effect adjacent the side walls 1. If desired, means may be provided in connection with the beam 13 to prevent the ash from accumulating under the same, downwardly-directed ash plows 70 21 being provided for this purpose in the form illustrated. These ash plows are inwardly inclined in a forward direction, with the result that when the beam is rotated, their outer surfaces crowd the ash 75 continually toward the outer portion of the ash-pit. Thus the formation of a stationary stratum of ash under the beam 13 is prevented, which layer or stratum otherwise might restrict the opening under the 80 producer side wall to such an extent as to interfere with the removal of ash containing clinkers of large size.

The invention also provides for stirring or agitating the bed of ash by means of one or more stirring arms 22, which are rotatable relative to the ash-bed and project up into the same a substantial distance, from underneath, thus breaking up clinkers within the ash bed, and agitating the same 85 to promote uniformity in its condition, whereby the air blast will pass up through the ash evenly to all parts of the fire-bed. These stirring arms 22 also act to break down any arches which may tend to form 90 between the producer side walls and the tuyère, and thus tend to keep the ash-bed in a condition where the ash may move progressively toward the ash-pit at a regular rate. In the present form the stirring arms 100 22 are carried by the beam 13 and the outer ones are bent outwardly to work adjacent the side walls 1, at which point the ash-bed usually is most in need of agitation. As appears in Fig. 2, I also prefer to incline the stirring arms 22 forwardly with regard to the direction of motion of the beam 13, whereby the arms tend to urge the ash 105 downwardly to the ash-pit 6, where it may be ejected by beam 13.

The invention also embodies means for removing the ash from the trough-shaped portion 9 of the ash-pit, preferably of such character that it may be combined advantageously with the ash-ejecting beam 13 and associated parts previously described, to the end that the operations of ejecting the ash from within the confines of side walls 1 and removing it from the trough 9 of the ash-pit may be conjointly carried on. One or 115 more scoops 23 are caused to travel along the trough-shaped portion 9 of the ash-pit, and provided with forward edges 24 which project down into trough 9 and raise the ash up on to a flat shelf 25. These scoops 120 conveniently may be attached to the gear ring 15 so that the rotary motion of this ring serves both to eject the ash from within the producer and remove it from the exterior portion of the ash-pit. As the beam 13 ro- 125

tates, the portion of the trough 9 corresponding to any given position of the beam will be freshly filled with ash; thus if all the scoops 23 were identical, the ones located immediately behind the ends 20 of beam 13, would remove the major portion of the ash. I prefer to pick up the ash substantially uniformly throughout the entire periphery of the side walls 1, by providing a number of scoops 23 spaced around the gear ring 15, the scoops which are located further behind the ends 20 of beam 13, having their forward edges projecting progressively deeper into the trough 9. Thus the three scoops of Fig. 3, for example, which pick up the ash moved into trough 9 by the left hand portion of the beam 13 when moved in the direction of the arrow in Fig. 2, have their forward edges 24 so disposed relative to each other that the lower left-hand scoop in Fig. 3 picks up the top layer of ash; and the two following scoops pick up successively the intermediate and lower layers of the ash, and at the same time the three scoops shown at the upper portion of Fig. 2 are removing the ash which has been pushed into trough 9 by the right-hand portion of the beam 13, as the same appears in Fig. 2.

Thus the ash is removed substantially uniformly throughout the entire periphery of the ash-pit.

After the ash has been picked up by scoops 23, it may be removed from their flat shelf-like surfaces 25 by means of a deflecting member 26 located in the path of travel of the scoop and at an angle thereto; in such manner that as the scoops move successively past such member, the ash carried by their shelves 25 will be scraped off and deposited or collected at the desired point. It will be noted that no parts of the scoops 23 project in such a way as to interfere with the motion of these scoops past the deflecting member 26, and thus this latter member may be made entirely firm and rigid as regards both vertical or lateral movements.

The above-described parts of the ash-ejecting apparatus serve to remove the ash at a uniform rate, which may be adjusted, however, to conform to the rate of gasification at which the producer is being operated. The stirring arms 22 continually agitate the ash-bed and assist in enabling the ash to descend evenly throughout the area of the ash-bed, while the ash-ejecting beam 13 sweeps over the ash-pit in such a way as to move the ash gradually out from underneath the side walls of the producer, where it is picked up by the scoops 23 which operate substantially simultaneously over the entire periphery of the trough-shaped portion 9 of the ash-pit. Thus the operation of removing the ash from the producer is accomplished without periodic disturbances of the

fuel-bed which tend to interfere with the gas-making operation, and the producer may be operated indefinitely without interruptions, such as are often required when the ash is removed intermittently.

In the present embodiment, the ash-ejecting beam 13 is shown as provided with forwardly-projecting teeth 13^a, which assist in breaking up the clinker underneath the side walls 1 of the producer, and also act to oppose a too rapid outward movement of the ash, thus making it possible for the beam 13 to be rotated continuously if desired without too rapid ejection of the ash.

The beam 13 and its arms also function to agitate the ash during rotation of the beam, and to push the ash ahead of the beam in such a way as to agitate the under part of the fire bed through the medium of the ash; in other words, although the beam does not directly contact with the under part of the fire bed, the ash above the beam is pushed as aforesaid to transmit motion upwardly to the under part of the fire bed, with the result that a wavelike disturbance travels around the ash and the under part of the fuel bed just ahead of the ash-ejecting beam.

While a specific embodiment of the invention has been described, it is obvious that many changes may be made without departing from its principle, as defined in the following claims.

I claim:

1. In combination, a gas producer having stationary side walls; a stationary ash pit and stationary tuyère hood, said side walls having associated therewith a lip projecting downwardly into the ash pit to provide a water seal for the interior of the producer, and means extending into said water seal for removing ash outwardly from under said side walls and past said lip to the portion of the ash pit exterior thereto.

2. In combination, a gas producer having stationary side walls, a stationary ash pit and tuyère hood, said side walls having associated therewith a lip projecting downwardly into the ash pit to provide a water seal for the interior of the producer, and means extending into said water seal for removing ash outwardly from under substantially the entire periphery of said side walls and past said lip to the exterior portion of the ash pit.

3. In combination, a gas producer having stationary side walls, a stationary ash pit located beneath said walls, said side walls having associated therewith a lip projecting downwardly into the ash pit to provide a water seal for the interior of the producer, and means for removing ash outwardly from under said side walls and past said lip to the portion of the ash pit exterior thereto, and additional means operating concentri-

- cally with the producer for removing the ash from said exterior portion of the ash pit.
4. In combination, a gas producer having stationary side walls, a stationary ash pit located beneath said walls, said side walls having associated therewith a lip projecting downwardly into the ash pit to provide a water seal for the interior of the producer, an outstroking ash-ejecting beam mounted to revolve under the side walls of the producer and extending outwardly past said lip, and a device located adjacent the outer end of the beam for revolving the same.
5. In combination, stationary gas producer side walls, a stationary ash pit located beneath the same, and side walls having associated therewith a lip projecting downwardly into the ash pit to provide a water seal for the interior of the producer, a rotatable ring mounted concentrically of the producer and exterior to said lip, and an outstroking ash-ejecting member connected to said ring and projecting inwardly into the ash pit to move the ash to the portion of the pit which is exterior to the lip.
6. In combination, a gas producer having stationary side walls, a stationary ash pit and stationary tuyère hood, said side walls having associated therewith a lip projecting downwardly into the ash pit to provide a water seal for the interior of the producer, an outstroking ash-ejecting beam disposed substantially diametrically of the producer, a rotatable gear ring substantially concentric with the producer side walls, said ash-projecting beam having its opposite ends joined respectively to the adjacent portions of said ring and having a center hub loosely enclosing the air tuyère of the producer.
7. In combination, gas producer side walls, a stirring arm extending upwardly a substantial distance into the ash from beneath said side walls and means for causing relative travel between said stirring arm and said side walls to agitate the body of ash within the producer, said stirring arm being forwardly inclined to urge the ash downwardly.
8. In combination, gas producer side walls, an ash pit located beneath the same, an outstroking ash ejecting beam mounted to work under the side walls of the producer, a stirring arm carried by said beam, said arm extending upwardly a substantial distance into the ash to agitate the body of ash within the producer and means for causing relative rotation between said side walls and said beam.
9. In combination, gas producer side walls, an ash pit located beneath the same, an outstroking ash ejecting beam mounted to work under the side walls of the producer, said beam carrying a downwardly directed ash plow adapted to force outwardly the ash contained within the ash pit underneath said beam.
10. In combination, stationary gas producer side walls, a stationary ash pit located beneath the same having a portion disposed exterior thereto, means for moving ash from within the confines of said walls to the portion of the ash pit exterior thereto, and means actuated by the same members as said ash moving means, for removing ash from said exterior portion of the ash pit.
11. In combination, stationary gas producer side walls, an ash pit located beneath thereof, a gear ring mounted substantially concentric with said side walls, adjacent the bottom thereof, and means carried by said gear ring for removing ash from said exterior portion of the ash pit.
12. In combination, stationary gas producer side walls, an ash pit located beneath said walls adapted to provide a water seal for the interior of the producer, means for moving ash outwardly from under said side walls to the portion of the ash pit exterior thereto, a gear ring mounted substantially concentric with said side walls adjacent the bottom thereof, and means carried by said gear ring for removing ash from said exterior portion of the ash pit.
13. In combination, stationary gas producer side walls, an ash pit located beneath said walls adapted to provide a water seal for the interior of the producer, a rotatable gear ring mounted substantially concentric with said side walls adjacent the bottom thereof, an outstroking ash ejecting beam mounted to revolve under the side walls of the producer and joined to said ring and means carried by said ring for removing ash from the portion thereof exterior to the producer side walls.
14. In combination, stationary gas producer side walls, an ash pit located beneath said walls adapted to provide a water seal for the interior of the producer, a gear ring mounted substantially concentric with said side walls adjacent the bottom thereof, an outstroking ash ejecting beam extending substantially diametrically beneath said side walls and having its opposite ends joined to said ring, said ring also carrying a scoop projecting into the portion of the ash pit exterior to the side walls to remove ash from such portion.
15. In combination, stationary gas producer side walls, an ash pit located beneath said walls adapted to provide a water seal for the interior of the producer, a gear ring mounted substantially concentric with said side walls adjacent the bottom thereof, an outstroking ash ejecting beam extending substantially diametrically beneath said side walls and having its opposite ends joined to

5 said ring, said ring also carrying a plurality of scoops extending progressively deeper into the portion of the ash pit exterior to the side walls to remove ash therefrom in successive stages.

16. In a gas producer, an ash pit having a trough shaped portion, a scoop having an inclined forward edge projecting thereinto and a flat shelf adapted to carry ash picked up by such edge, means for moving said scoop along said trough-shaped portion, and a stationary deflecting member located in the path of travel of the scoop having a fixed sweep adapted to push ash laterally 15 from off said shelf.

17. In combination a gas producer having stationary side walls, a stationary ash pit located beneath the same having a trough-shaped portion exterior to said walls, 20 a rotatable gear ring mounted substantially concentric with the producer side walls and adjacent the bottom thereof, an outstroking ash ejecting beam mounted to revolve under said side walls and having its opposite ends joined to said ring, said ring also carrying a plurality of scoops extending into the portion of the ash pit exterior to the side walls to remove ash therefrom in successive stages and a deflecting member located in the path 25 of travel of said scoops adapted to remove ash laterally therefrom.

18. In combination, gas producer side walls, an ash-ejecting beam adjacent the bottom of the walls, a stirring arm extending from said beam upwardly a substantial distance into the ash from beneath said side walls and means for causing relative travel between said stirring arm and said side walls to agitate the body of ash within the 40 producer.

19. In combination, gas producer side walls, an ash pit located beneath said walls having an annular trough-shaped portion disposed exterior thereto, and rotary means 45 exterior to the producer walls for removing ash from points around the periphery of said trough-shaped portion.

20. In combination, stationary gas producer side walls, an ash-pit located beneath said walls having an annular portion disposed exterior thereto, means acting continuously beneath said side walls for removing the ash outwardly from underneath the same to the portion of the ash-pit exterior thereto, and additional means operating continuously at substantially all points around said exterior portion of the ash-pit for removing ash therefrom.

21. In combination, stationary gas producer side walls, an ash-pit located beneath said walls having an annular portion disposed exterior thereto, means for continuously stirring the ash within said side walls, means acting continuously beneath said side walls for removing the ash outwardly from

all points underneath the same to the portion of the ash-pit exterior thereto, and additional means operating continuously at all points around said exterior portion of the ash-pit for removing ash therefrom. 70

22. In combination a gas producer having stationary side walls, a stationary ash pit located beneath the same, said walls having a lip adapted to provide a water seal for the interior of the producer, an outstroking 75 ash-ejecting beam mounted to revolve under the side walls of the producer, and means located exterior to said lip for revolving said beam.

23. In combination a gas producer having stationary side walls, a stationary ash pit located beneath said walls adapted to provide a water seal for the interior of the producer, an outstroking ash-ejecting beam mounted to revolve under the side walls of 85 the producer, and means operating in the portion of the ash pit which is exterior to the side walls, to pick up and discharge ash from points in the ash pit which are intermediate the active portions of the beam. 89

24. In combination a gas producer having stationary side walls, an annular stationary ash pit located adjacent the bottom of said side walls and providing a water seal for the interior of the producer, means operating evenly all around the producer for forcing ash underneath said side walls, and means operating evenly all around the portion of the ash pit which is exterior to the producer walls, for picking up the ash located in the pit. 100

25. In combination, stationary producer side walls, a stationary ash pit located beneath the said side walls having associated therewith a lip projecting downwardly into the ash pit to provide a water seal for the interior of the producer, an ash-ejecting member extending substantially radially of the producer and located beneath said water seal, but having its ends projecting upwardly 110 above the outward portion of the water seal, and means connected to the ends of said member for actuating the same. 105

26. In combination, a gas producer having stationary side walls, a stationary ash pit 115 and tuyère hood located beneath said walls, said side walls having associated therewith a lip projecting downwardly into the ash pit to provide a water seal for the interior of the producer, an annular ash carrier located adjacent the outer portion of the ash pit and adapted to support the ash removed from the ash pit, means for rotating said carrier concentrically with the producer, means for removing ash from the ash pit to said carrier, and a deflecting member located in the path of travel of said carrier for sweeping the ash therefrom. 120

27. In combination, stationary gas producer side walls, revolvably mounted stirring

arms extending upwardly a substantial distance into the ash from beneath said side walls, a tuyère hood disposed substantially centrally of the producer, one of said stirring arms operating in a path adjacent the tuyère hood and another of said stirring arms operating in a path adjacent the side walls of the producer.

28. The combination set forth in claim 27, wherein said stirring arms are carried by an ash-ejecting beam working under the side walls of the producer.

29. In combination, a gas producer having stationary side walls, a stationary ash pit located beneath said walls, said side walls having associated therewith a lip projecting downwardly into the ash pit to provide a water seal for the interior of the producer, an outstroking ash-ejecting beam mounted to revolve under the side walls of the producer, said beam being spaced from the bottom of the ash pit, and means for maintaining a loose condition of the ash underneath said beam.

30. In combination, a gas producer having stationary side walls, a stationary ash pit located beneath said walls, said side walls having associated therewith a lip projecting downwardly into the ash pit to provide a water seal for the interior of the producer,

an outstroking ash-ejecting beam mounted to revolve under the side walls of the producer, said beam being spaced from the adjacent above-mentioned parts of the producer, and means disposed outwardly of said lip for supporting said beam and for rotating the same.

31. In combination, a gas producer having an outstroking ash-ejecting beam disposed adjacent the bottom of the producer side walls, means for producing relative rotation between said beam and the contents of the producer, said beam carrying forwardly directed toothlike projections adapted to engage the ash and prevent too rapid outward movement thereof.

32. In combination, a gas producer having an outstroking ash-ejecting beam disposed adjacent the bottom of the producer side walls, means for producing continuous relative rotation between said beam and the contents of the producer, said beam carrying forwardly directed toothlike projections adapted to engage the ash and prevent too rapid outward movement thereof.

In testimony that I claim the foregoing, I have hereunto set my hand this 8th day of July, 1921.

WILLIAM B. CHAPMAN
